UNITED STATES PATENT OFFICE

JAMES B. MCCOMB, OF SCARSDALE, NEW YORK

BUG CLEANING COMPOSITION

No Drawing.

Application filed July 24, 1928. Serial No. 295,118.

This invention relates to a cleaning composition designed primarily for use in cleaning and renovating rugs, but it is to be understood that a composition, in accordance with this invention may be employed for cleaning and renovating any character of fabric for which it is found applicable, and the invention has for its object to provide, in a manner as hereinafter set forth a composition of 10 the class referred to capable, when employed upon a rug or carpet, to satisfactorily and expeditiously cleanse and renovate the same, and at the same time preserve the rug or carpet and leave it in a cleaner and sounder 15 condition than when other cleaning preparations are employed.

A cleaning composition, in accordance with this invention is an improvement upon that disclosed in Letters Patent 1,172,297. 20 The composition as set forth in the patent aforesaid is of powdered form, whereas the composition in accordance with this invention is in granular form which possesses a material advantage over the powder in that 25 the latter when it is thrown on top of a pail of hot water portions of it cling together, forming lumps which the houseman or the operator, carrying out the cleansing operation would not take the time to dissolve, with 30 the result that these lumps were scrubbed into the rug or carpet, matting the nap and resulting in dissatisfaction. By setting up the 35 composition of granular form, free play of the hot water is allowed between the particles and the old difficulty is eliminated and all ingredients are dissolved, which of course, gives better results than if only a part of the 40 ingredients are dissolved.

A further object of the invention is to provide, in a manner as hereinafter set forth, a 45 cleaning composition for the purpose referred to which will permit of the rugs or carpets being cleaned without being removed from the floor.

A further object of the invention is to provide, in a manner as hereinafter set forth, a 50 cleaning composition for the purpose referred to employed in the form of a shampoo for cleaning and renovating purposes and possessing a characteristic to quickly dry, under

such conditions expediting the cleansing and renovating operations.

A further object of the invention is to provide, in a manner as hereinafter set forth, a 55 cleaning composition for the cleaning of dyed fabrics from the surface thereof; further to provide a more satisfactory medium for renovating and cleansing purposes than that obtained by the employment of soap, gasoline, benzine, ether and alcohol, and furthermore one that is economical and conveniently used.

A cleansing composition, in accordance 60 with this invention, consists of white neutral soap, borax, trisodium phosphate, sesqui carbonate of soda, ultramarine blue and cedar oil. The soap is in the form of coarse granules, the borax granulated, the trisodium phosphate in the form of crystals as well as the sesqui carbonate and the ultramarine blue 65 is powdered. The soap is ground, not powdered.

Preferably the proportions of the several 70 ingredients are as follows:

White neutral soap, coarse granules	24 lbs.
Borax, granulated	4 lbs.
Trisodium phosphate, crystals	2 lbs.
Sesqui carbonate of soda, crystals	1 lb.
Ultramarine blue, powdered	4 ounces
Cedar oil	4 ounces

The white neutral soap, borax, trisodium phosphate, sesqui carbonate of soda and ultramarine blue are placed into a rotary mixer and the same is operated for the necessary period to form a thorough mixing of the ingredients referred to, preferably a thorough mixing of the several ingredients is had in from two to five minutes. The cedar oil is 85 then dropped into the mixture and the machine allowed to operate for two or three minutes and this completes the mixing process.

When used, ten ounces of the composition 90 is dissolved in four gallons of hot water and the resulting solution applied to the rug or carpet with a coarse sponge. The sponge in the hand of the operator works up a copious creamy lather, which cleanses thoroughly and restores the sheen and color without injuring 95

the nap, especially of a fine silk oriental rug. Injury is had to the nap if a brush is used instead of the sponge. The shampoo works a chemical change on the dirt, leaving it in powdered form to be swept off when dry, so that no rinsing or scraping is required. The ingredients forming the composition provide for a quicker and more efficient result with less labor and free from the harshness, which would be the case if soda ash was employed as one of the ingredients of the composition.

It is the shampoo lather which accomplishes the cleansing and renovating functions and when using the composition it does not necessitate the wetting of the carpet or rug with a brush, as this is a great advantage to hotels where rugs are principally used, because by the use of the composition in accordance with this invention, the rugs or carpets become dry quickly and no loss of rentals results from rooms being out of order over night. The composition is such that it readily removes iodine, pitch, grease, paint, tar, etc., from a soiled carpet or rug.

It is thought the many advantages of a cleaning composition, in accordance with this invention and for the purpose set forth can be readily understood, and although the preferred embodiment of the invention is as illustrated and described, yet it is to be understood that changes in the details of construction can be had which will fall within the scope of the invention as claimed.

What I claim is:

- 35 1. A cleaning composition for removing dirt in powdered form from and for restoring the sheen and color of a rug or carpet without removing the latter from the floor and injuring its nap consisting of a body of white neutral soap in the form of coarse granules, granulated borax, trisodium phosphate crystals, sesqui carbonate of soda crystals, powdered ultramarine blue and cedar oil.
- 40 2. A cleaning composition for removing dirt in powdered form from and for restoring the sheen and color of a rug or carpet without removing the latter from the floor and injuring its nap consisting of a body of white neutral soap in the form of coarse granules, granulated borax, trisodium phosphate crystals, sesqui carbonate of soda crystals, powdered ultramarine blue and cedar oil in the proportions of twenty four pounds of soap, four pounds of borax, two pounds of trisodium phosphate crystals, one pound of sesqui carbonate of soda crystals, four ounces of ultramarine blue and four ounces of cedar oil.

In testimony whereof, I affix my signature hereto.

60 JAMES B. McCOMB.
